KNIFE SHARPENER

Emerson E. Case, Perry, N. Y.

Application March 15, 1945, Serial No. 582,857

2 Claims. (Cl. 51—214)

1

This invention relates to a knife sharpener, and more particularly to a knife sharpening rack which may be constructed to receive one or any number of knives of varying widths and so arranged that the insertion and withdrawal of a knife will properly hone the edge to maintain the knife in good condition.

An object of the invention is to provide a device suitable for use in kitchens or commercial establishments in which knives can be safely kept readily available for use as desired.

A further object is to provide in conjunction with such a case sharpening means so arranged that the passage of the knife blade into and out of the device will be effective to hone the cutting edge.

Other subsidiary objects will more particularly appear in the course of the following detailed description.

The invention consists in the novel construction, arrangement and combinations of parts hereinafter more particularly described and claimed.

One sheet of drawings accompanies this specification as part thereof in which like reference characters indicate like parts throughout.

In the drawing:

Figure 1 is a perspective view of a knife holder adapted to receive and sharpen several knives;

Figure 2 is a transverse vertical cross-section taken on line 2—2 of Figure 1;

Figure 3 is a fragmentary perspective view of an upper corner of the device with the top partly broken away and the side removed; and

Figure 4 is a fragmentary plan view looking down on Figure 3.

In the embodiment of the invention illustrated in the accompanying drawing, a container is provided comprising side walls 1—1 connected at the top by a narrow back wall 2 associated with a hinged back wall door portion 3, a bottom 4, a top 6 and a front transparent panel 5 which may be secured in a frame 5'.

An attachment strip 15 having spaced orifices 16 may conveniently be secured to the narrow back portion 2 by means of which the entire container can be supported by nails or screws from a wall surface.

The top member 6 is preferably formed with a down-turned lip 7 at its forward edge adapted to contact the upper face of a member 11 which extends the full width and depth of the container between the end walls 1—1.

By reference to Figure 2 it will be noted that by this construction the lip 7 spaces the block 11

from the main body of the top 6 and in this space is secured against the back wall member 2 a plurality of blocks 9 having angularly disposed side walls to which are secured hone members 10. By reference to Figure 3 it will be observed that the hone members 10 positioned in the notched space between two of the block members 9 are positioned one above the other, so that these hone members 10 intersect as illustrated in Figure 4.

Notches 8 are provided in the top member 6 and similar notches 12 are provided in the member 11, the notches 8 and 12 being arranged in pairs in vertical alignment with the space between adjacent blocks 9—9 to form slots longer and wider than the cross-section of the knife blade to permit free insertion of the knife.

Secured against the forward end of edge of the notches 12 in the member 11 are resilient spring members 13 having their free ends extending downwardly and which are adapted to bear against the back edge of a knife blade B as the knife K is positioned in the container.

In operation a knife blade B is inserted in one of the slots 8 in the top member 6 and as it passes through the superposed slots 8 in the members 6 and 12 and the member 11 its back edge is engaged by the resilient spring member 13 which forces the blade rearwardly so that its cutting edge engages between the hones 10—10 associated with that particular pair of slots. By reason of the hones of each pair intersecting as illustrated it will be observed that there is no trough bottom for the knife edge to contact but that the edge successively engages on opposite sides the superposed hones 10—10.

It will also be observed that this device requires no attention upon the part of the operator with respect to the honing operating, inasmuch as the mere insertion of the knife operates to effectively hone the edge both on the insertion movement and on the withdrawal movement by reason of the automatic pressure of the blade by resilient member 13 into honing relationship with the hone members 10—10.

While in the foregoing description the sharpening elements have been referred to as hones, the invention is not restricted to any particular sharpening element or device, being adaptable to use with file members, abrasive powders glued to a supporting base, emery cloth or the like.

Having thus described my invention, I claim:

1. Knife sharpening rack comprising a container enclosing a chamber in which to sheathe the blade of a knife, a wall of said container having a slot giving access to said chamber, said slot

being elongated in a front to back direction and having its cross-sectional area longer and wider than the blade which it is adapted to accommodate to permit easy insertion of said blade, a pair of opposed hones within said chamber below said slot, angularly arranged one above the other with their adjacent endslapping, and their working faces in planes which form a dihedral angle whose apex intersects the area of said slot near the back end of the latter, and a spring within said chamber adjacent said hones, fixed to said container below the front end of said slot, having a yielding portion extending toward said apex so that the distance from said yielding portion to

said apex is normally less than the length dimension of the cross-section of the knife blade, whereby said knife blade is pressed by said spring toward said hones and guided to a position coincident with the bisecting plane of said dihedral angle should it be inserted inclined with respect to said bisecting plane.

5 2. Knife sharpening rack as claimed in claim 1, said spring being a leaf spring fixed at its upper 10 end with its free end directed downwardly from said slot, and said hones being confined to a relatively narrow zone above the lower end of said chamber.

EMERSON E. CASE.
